UNITED STATES PATENT OFFICE.

VICTOR H. JENNINGS, OF WORCESTER, MASSACHUSETTS, ASSIGNOR, BY MESNE ASSIGNMENTS, TO UNIVERSAL PATENTS COMPANY, OF WOONSOCKET, RHODE ISLAND, A CORPORATION OF RHODE ISLAND.

WOVEN CARRIER.

1,250,886.

Specification of Letters Patent. Patented Dec. 18, 1917.

Application filed August 2, 1916. Serial No. 112,835.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Carriers, of which the following is a specification, reference being had therein to the accompanying drawings.

10 My invention has relation to carriers which are woven with pockets adapted to serve as receptacles, more especially (though not exclusively) ammunition carriers having pockets designed to contain cartridges. The 15 main principles of the invention may be embodied in a carrier having one pocket, but a more important embodiment thereof is in a carrier having a plurality of pockets in a continuous series and either made up 20 in the form of a cartridge-carrier or belt for use in a machine-gun, or in a form to be worn as a carrier for ammunition.

The invention is, more particularly, an improvement in woven carriers of the type 25 in which a pocket is in the form of a tubular loop that stands out bodily from one surface of a supporting web and is adapted to contain a single cartridge. It provides a carrier of this type in which a portion of the 30 length of the said outstanding tubular loop is of a smaller diameter constituting a constriction which is adapted to fit a portion of reduced diameter of the article inserted into the pocket. For instance, when an 35 embodiment of the invention is used as a cartridge-carrier, the said constriction fits the small diameter of a cartridge at its bullet-end, as is desired especially in the case of the cartridge-carriers or belts that 40 are used in machine-guns.

The invention consists, further, in a woven carrier comprising a supporting web and a pocket or series of pockets each constituted by a tubular loop, integral with the 45 said web, standing out from one surface of the latter, with the sides of one portion of the outstanding tubular loop springing from the web on lines separated by a plurality of picks of the web, producing thereby in such 50 portion an arch of comparatively wide spread, and with the sides of an adjoining portion of the said loop springing from the web on a narrow base in connection with

the web and producing a constriction of relatively-reduced diameter. 55

Other improvements constituting features of the invention are set forth in claims at the close of this specification.

One general object of the invention is to produce a woven carrier having a pocket 60 which, in addition to having a construction adapted to fit a reduced portion of the article that is inserted into the pocket, as for instance the bullet-end of a cartridge, shall be of a character to remain open at its 65 entrance or mouth-end so as to facilitate the introduction of the article. This is of especial importance in the case of a cartridge-carrier or belt for use in a machine- 70 gun. The attainment of the said object in the case of machine-gun cartridge-carriers or belts facilitates the loading of the latter by automatic machinery, and avoids the drawbacks of the carriers or belts now in use. These latter are composed of tapes 75 fastened together by binders at intervals so as to leave slits to receive cartridges, and they present difficulties in the loading owing to the tendency of the two tapes to close together so as to render it difficult to find 80 and enter the slits. The invention has other objects, both general and special, among which are that of dispensing with the metal binders which heretofore have been employed in making machine-gun carriers or 85 belts, and that of producing a strong and serviceable low-cost machine-gun carrier or belt which will be fit to stand repeated re-loading and firing operations and outlast carriers or belts such as now are in use. 90

The drawings represent an illustrative embodiment of the invention in a machine-gun cartridge-carrier or belt, which embodiment in itself constitutes one part of the invention. They also show in separate 95 views other parts or features of the invention.

In the drawings,—

Figure 1 is an isometric view of a portion of a cartridge-carrier or belt for machine-guns containing the said embodiment, with three cartridges held or carried thereby. 100

Fig. 2 is a view of a short length of the said carrier or belt, looking at the large 105 ends of the pockets or loops.

Fig. 3 is a view thereof looking at the

small ends or constrictions of the pockets or loops.

Fig. 4 is a diagram illustrative of a weave which may be adopted in practice, looking at 5 the large end of a pocket or loop.

Fig. 5 is a similar diagram looking at the small end or constriction of a pocket or loop.

Fig. 6 is a diagram on line 6, 6, of Fig. 4, 10 with the two plies brought close together.

Fig. 7 is a diagram showing a modification in the binding of the two web-plies together adjoining the constriction of a loop or pocket.

15 Fig. 8 is a diagram showing a modified fabric construction by which the small end of a pocket or loop is rendered proportionately larger and produced with a wider base.

Fig. 9 shows a portion of a machine- 20 gun belt embodying the invention, partly rolled up.

Having reference to the drawings, —

The supporting-web 1 upon which the loops or pockets 2, 2, etc., are formed is in 25 this instance, in practice, of the continuous length that is required for use in a machine-gun. See Fig. 9. In other instances, the said web will be of a length suitable to the desired kind of carrier or belt and the 30 number of loops or pockets with which the latter is furnished; thus, when the reception and support of but a single article are to be provided for, the length of web of a carrier will be only such as is required for the 35 proper application, attachment, or the like of the single loop or pocket that in that case will be employed. As usual in woven carriers, the length of the loops or pockets 2, 2, extends transversely across the web 1, such 40 length corresponding with such width or varying therefrom according as may be desired. The constriction 2^a, of each loop or pocket is of any desired width in practice, either relatively greater or less than in Fig. 45 1 of the drawings, as may be found necessary or advisable. It preferably constitutes one end-portion of the loop or pocket, but in the case of carriers for other special purposes it may be located between the ends 50 of the loop or pocket. The correspondence in form between the loop with its constriction, and the portions of a cartridge which occupy the loop, is shown clearly in Fig. 1, which shows also the manner in which the 55 constriction limits the extent of the entrance of the cartridge into a loop or pocket, and the absolute uniformity in the positions of the cartridges x, x, x, in the series applied to a multiple-loop or pocket carrier or belt.

60 So far as the broad aspects of the invention are concerned, the weave or weaves adopted in practice in producing the supporting web and one or more loops or pockets with constrictions, integral with the 65 supporting-web, may vary. Any approved

type or types of weave may be adopted as preferred or as circumstances may dictate, except in those instances in which the special features of invention which are claimed separately hereinafter are material. The 70 drawings show the supporting web between and adjoining the loops or pockets as of two-ply weave with the two plies tied together by means of binder warps, and with the loops or pockets formed of one of the 75 said plies, which is woven separately for the production thereof. The number of plies is not material, while in some thereof the warp-threads employed for the loops or pockets may be buried between plies of the 80 web intermediate one loop or pocket and the next, or may be tied in at the sides of the loops or pockets and floated at the back of the web between one loop or pocket and the next, and subsequently be cut off. Either 85 a single-shuttle loom may be employed for the weaving, or a two-shuttle loom, and the mode of weaving adopted in practice will be such as to suit the number of shuttles employed.

90 In producing a web having a loop or pocket with constriction, of the weave that is shown in Figs. 4 and 5, the two plies of the web are woven coextensively, from right to left in Fig. 5, which is left to right in Fig. 4, to and including the picks x, y, such plies being duly bound together, as by binder warps z, which latter in this case engage with the pick x of the upper ply across the entire width of web, as they also do with 100 alternate upper-ply picks preceding pick x. For the next two picks 1, 2, and 1^a, 2^a, in both plies following picks x, y, the upper 105 ply is woven unconnected with the lower ply as shown in Fig. 4, in the part of the former 110 ply pertaining to the portion of large diameter of the loop or pocket, but bound to the lower ply, as shown in Fig. 5, in the part 115 of the upper ply which is adjacent to the constriction. Thereafter for a number of picks (3 to 19, inclusive) the upper ply is woven entirely unconnected with the lower 120 ply throughout the entire length of the loop or pocket, while a smaller number of picks, in this instance one pick, 19^a, is woven in 125 the lower ply. The absence of connection between the two plies is indicated in Fig. 6. Then for two picks 20, 21, and 20^a, 21^a, in each ply, the upper ply is woven unconnected with the lower ply in the large portion 130 of the loop or pocket, as in Fig. 4, but bound thereto in the portion adjacent to the constriction as in Fig. 5. Then beginning with picks x', y', the two plies are woven bound together, as at the right in Fig. 4 and left in Fig. 5, and so on.

135 In some cases, instead of producing the constriction by binding the two plies together by binder warp-threads at opposite sides of the small end of the loop or pocket,

across intermediate portions of the distance that is subtended by the arc constituted by the portion of larger diameter, I may bind such portions of the two plies together by 5 means of binder-picks of weft, as in Fig. 7.

On comparison of Figs. 4 and 5 it will be observed that in the present embodiment of the invention the wall of the loop or pocket is of uniform thickness from end to end of 10 the latter.

As a result of binding the picks 1, 2, 20 and 21, of the upper ply to the lower ply for a portion of the length of the loop or pocket, but leaving them unbound to the 15 lower ply for the remaining portion of the said length, the loop or pocket is made smaller in the place where the constriction is desired than in the main or full-size portion thereof. As is apparent in Figs.

20 4 and 5, the outstanding wall of the loop or pocket contains fewer picks of weft in the constricted end-portion than elsewhere. The sides of the portion of large diameter spring from the web on lines that are sepa-

25 rated from each other by a space corresponding with a plurality of picks in the lower ply of the web, producing thereby an arch that is comparatively wide-spread at its base. Those of the portion of smaller

30 diameter, namely the constriction, spring from the web on lines more closely adjoining each other; in this instance immediately adjoining. Thus the constriction has a narrow base in connection with the web, where-

35 as the large-diameter portion has a comparatively broad base. This broad base prevents the loop or pocket from displacing or overturning sidewise, which is a liability in the case of a loop or pocket connected

40 with the supporting web by a narrow neck or base as in Fig. 5 throughout the entire length of the loop or pocket. This liability would be undesirable in the case of various carriers, and especially so, and inconvenient,

45 in the case of machine-gun carriers or belts, on account of the resulting difficulty in automatically loading such carriers or belts, and on account of the drawbacks or disadvantages incident to displacement of the

50 loops or pockets in a machine-gun when engaged and acted upon by the pusher-devices of the latter.

When the features of the invention are embodied in a machine-gun carrier or belt, 55 as well as in various other embodiments of the said features, the outstanding loops or pockets are open at both ends, although in some embodiments the loops or pockets may be closed at one end. To prevent the sel-

60 vage warp at the constricted end of a loop or pocket from being broken by the expansion due to the entrance of a cartridge, and to obviate cutting or abrasion by the rough or hard edges of the small ends of the shells 65 of cartridges. I employ a strong warp-

yarn or thread *b*, preferably one of linen. I have obtained successful results with a 5-ply linen thread.

In Fig. 8 a small end or constriction is made larger in diameter than in Fig. 5 by 70 reason of having the picks 20, 21, unbound to the back ply at one side of the loop or pocket.

I claim as my invention,—

1. A woven carrier comprising a support- 75 ing web and a pocket constituted by a loop standing out from one surface thereof, the said outstanding pocket-loop woven integral with the said web, of one diameter for a portion of its length and of a smaller diam- 80 eter for a second portion thereof constituting a constriction, with the sides of said portion of larger diameter springing from the web on lines separated by a plurality of picks of the web, producing thereby an arch 85 of comparatively wide spread, and with those of the said portion of smaller diameter or constriction springing from the web on lines more closely adjoining each other.

2. A woven carrier comprising a support- 90 ing web and a series of pockets constituted by loops woven integral therewith and standing out from one surface thereof, and each of one diameter for a portion of its length and of a smaller diameter for a sec- 95 ond portion thereof constituting a constric- 100 tion, with the sides of said portion of larger diameter springing from the web on lines separated by a plurality of picks of the web, producing thereby an arch of comparatively wide spread, and with those of the said smaller diameter or constriction springing from the web on lines more closely adjoining each other.

3. A woven carrier comprising a web and 105 a pocket constituted by a loop standing out from one surface thereof, the said outstanding loop woven integral with the said web, open at both ends, of one diameter for a portion of its length and of a smaller diam- 110 eter for a second portion thereof constituting a constriction, with the sides of said larger diameter springing from the web on lines a distance apart, and with those of the said smaller diameter or constriction 115 springing from the web on lines close together.

4. A woven carrier comprising a support- 120 ing web and a series of pockets constituted by loops standing out from one surface thereof, the said outstanding loops woven integral with the said web, each open at both ends, of one diameter for a portion of its length and of a smaller diameter for a second portion thereof constituting a constriction, with the sides of said larger diameter springing from the web on lines a distance apart, and with those of the smaller diameter or constriction springing from the 125 web on lines close together. 130

- 4
5. A woven carrier comprising a web and a pocket constituted by a loop standing out from one surface thereof, the said outstanding loop woven integral with the said web with the sides at one portion of its length springing from the web on lines separated by a plurality of picks of the web, producing thereby an arch of comparatively wide spread, and having a constricted second portion of its length with its sides springing from the web on lines immediately adjoining each other. 55
6. A woven carrier comprising a supporting web and a series of pockets constituted by loops standing out from one surface thereof, the said outstanding loops woven integral with the said web, each loop having the sides of one portion of its length springing from the web on lines separated by a plurality of picks of the web, producing thereby an arch of comparatively wide spread, and having a constricted second portion of its length with its sides springing from the web on lines immediately adjoining each other. 70
7. A woven carrier comprising a web and a pocket constituted by a loop standing out from one surface thereof, the said outstanding loop woven integral with the said web and with the walls thereof of uniform thickness from end to end, with the sides of one portion of its length springing from the web on lines separated by a plurality of picks of the web, producing thereby an arch of comparatively wide spread, and having a constricted second portion of its length with its sides springing from the web on lines immediately adjoining each other. 75
8. A woven carrier comprising a supporting web and a series of pockets constituted by loops standing out from one surface thereof, the said outstanding loops woven integral with the said web and with the walls of each thereof of uniform thickness from end to end, each loop having the sides of one portion of its length springing from the web on lines separated by a plurality of picks of the web, producing thereby an arch of comparatively wide spread, and having a constricted second portion of its length with its sides springing from the web on lines immediately adjoining each other. 80
9. A woven carrier comprising a web and a pocket constituted by a tubular loop standing out from one surface thereof, the said outstanding loop woven integral with the said web and with the sides of one portion springing from the web on lines separated by a plurality of picks of the web whereby such portion is spread widthwise, and having an adjoining portion which is constricted by its sides springing from a narrow base in connection with the said web. 85
10. A woven carrier comprising a supporting web and a series of pockets constituted by tubular loops standing out from one surface thereof, and woven integral therewith, and with the sides of one portion of each outstanding loop springing from the web on lines separated by a plurality of picks of the web whereby such portion is spread widthwise, and with an adjoining portion constricted by the sides thereof springing from a narrow base in connection with the said web. 90
11. A woven carrier comprising a web and a pocket constituted by a tubular loop open at both ends standing out bodily from one surface thereof, the said outstanding loop having an end-extension of smaller diameter constituting a constriction. 95
12. A woven carrier comprising a continuous supporting web and a series of pockets constituted by tubular loops open at both ends standing out bodily from one surface thereof, each of said outstanding loops having an end-extension of smaller diameter constituting a constriction. 100
13. A woven carrier comprising a supporting web and a pocket constituted by a loop open at both ends, standing out from one surface of said web, and having fewer picks of weft in one end-portion thereof than elsewhere thereby producing a constricted end-section. 105
14. A woven carrier comprising a continuous supporting web and a series of pockets each constituted by a loop open at both ends, said pocket-loops standing out from one surface of the web and each having fewer picks of weft in one end-portion thereof than elsewhere thereby producing a constricted end-section. 110
15. A woven carrier comprising a web and a pocket constituted by a loop open at both ends woven integral with the said web, with the sides of one portion of said loop springing from the web on lines separated by a plurality of picks of weft, and having a constricted adjoining portion with its sides springing from a narrower base in connection with the web and containing fewer picks of weft than the first portion. 115
16. A woven carrier comprising a supporting web and a series of pockets constituted by loops integral therewith, each loop open at both ends, with the sides of one portion of a loop springing from the web on lines separated by a plurality of picks of weft and those of a second portion springing from a narrower base in connection with the web, the said second portion containing fewer picks of weft. 120
17. A woven carrier comprising a web and an outstanding pocket having a section of relatively-reduced diameter constituting a constriction, said pocket formed of a loop which springs from the web on lines that

are widely spaced apart in the portion of larger diameter and that are close together in the constriction.

18. A woven carrier comprising a web and an outstanding pocket having a section of relatively-reduced diameter constituting a constriction, said pocket formed of a loop which in the portion of larger diameter 5 springs from the web on lines that are separated by a space, and at the constriction is 10 rated by a space, and at the constriction is

bound to the remainder of the web across intermediate portions of the distance subtended by the said larger portion and springs from the web on lines that are close together.

In testimony whereof I affix my signature 15 in presence of two witnesses.

VICTOR H. JENNINGS.
